UNITED STATES PATENT OFFICE

127,537

DESIGN FOR A PIN OR ANALOGOUS ARTICLE

Providence Johnnides, Woodside, Long Island,
N. Y.

Application August 6, 1940, Serial No. 94,259

Term of patent 3½ years

To all whom it may concern:

Be it known that I, Providence Johnnides, a citizen of the United States, residing at and whose post-office address is 43-23 68th Street, Woodside, Long Island, New York, have invented a new, original, and ornamental Design for a Pin or Analogous Article, of which the following is a specification, reference being had to the accompanying drawing, forming a part thereof.

Figure 1 of the drawing shows a front view of the pin or analogous article showing my new design and Figure 2 shows a cross section thereof taken on line 2—2 of Fig. 1.

I claim:

The ornamental design for a pin or analogous article, as shown.

PROVIDENCE JOHNNIDES.
